Primary Examiner — L. A. Grabenstetter*Assistant Examiner* — Danielle Nichole Bowly(57) **CLAIM**

The ornamental design for a book alignment tool as shown and described.

DESCRIPTION

FIG. 1 is a front view of a book alignment tool showing my new design;

FIG. 2 is a rear view of the book alignment tool;

FIG. 3 is a right side view of the book alignment tool;

FIG. 4 is a left side view of the book alignment tool;

FIG. 5 is a top view of the book alignment tool;

FIG. 6 is a bottom view of the book alignment tool;

FIG. 7 is a top front side perspective view of the book alignment tool; and,

FIG. 8 is a top front side perspective view of the book alignment tool in use.

The broken lines in FIG. 8 are illustrative of environmental structures forming no part of the claimed design.

1 Claim, 4 Drawing Sheets
